UNITED STATES PATENT OFFICE.

ERNEST H. VINCENT, OF OAKLAND, CALIFORNIA.

STEAM BOILER.

Application filed June 1, 1923. Serial No. 642,831.

This invention relates to steam boilers and particularly pertains to the type of boiler disclosed in my United States Letters Patent No. 1,351,500, dated August 31, 1920. Such a boiler is adapted for automotive and marine work and is composed of a plurality of duplicate tube units assembled to form a boiler of desired capacity wherein steam may be economically generated.

It is the principal object of the present invention to generally improve boilers of the type referred to whereby to provide a boiler of simple and efficient construction which is designed to expedite the circulation of water therein and operate with maximum efficiency.

The invention contemplates the use of a multiplicity of water tubes arranged in units which are connected in a novel manner to allow for expansion caused by heat; the tubes of the units are interconnected in a manner affording maximum circulation of water therein which consequently increases the steam generating capacity thereof.

One form which the present invention may assume is exemplified in the following description and illustrated by way of example in the accompanying drawings, in which:

Fig. 1 is a view in section showing an elevation of a boiler embodying the invention.

Fig. 2 is a side elevation of the same.

Fig. 3 is a fragmentary bottom view of the boiler structure disclosing certain details of construction.

Referring to the drawings, 10 indicates a housing, here shown as rectangular in formation and providing a lower heat chamber 11 disposed beneath a boiler structure 12, and an upper chamber 13 above this boiler. A heat inlet opening 14 communicates with the chamber 11 and an outlet opening 15 leads from the upper chamber 13, thereby providing a complete circulation of heat through the structure.

As shown in the drawings, the entire housing 10 is enclosed by an outer metal wall 16, while the inner walls of the housing are here shown as separated along lines 17 and 18 to permit the removal of the lower chamber 11 and the upper chamber 13 and to thereby allow ready access to the bottom of the boiler structure 12 and the top thereof. Angle plates 19 are utilized to secure these wall sections together by means of bolts 20.

The boiler structure comprises a plurality of combined water and heat circulating units 21. One of these units is clearly shown in Fig. 1 and will be seen to comprise a plurality of vertical water tubes 24 connected to horizontal upper and lower headers 22 and 23 which latter are preferably formed rectangular in cross section.

It will be understood that the headers 22 and 23 of the various units are arranged at spaced distances apart in parallel relation to each other crosswise of the housing and in this particular instance crosswise of a vehicle frame.

Through the lower wall of each tube 22 a plurality of small openings 25 are formed. These openings receive flue tubes 26 which extend upwardly and pass through the water tubes 24. The water tubes 24 are preferably welded with their lower ends through openings in the upper wall of the lower headers 22. As shown in Fig. 1 the tubes 26 are considerably longer than the water tubes 24 and extend upwardly through the upper headers 23 where they are suitably expanded within openings 27 formed along the upper wall of the headers 23. Thus it will be seen that continuous communication is established between the heat chamber 11 and the upper chamber 13 and at the same time communication will be established between the lower headers 22 and the upper headers 23 of each boiler unit. By the expression "boiler unit" is implied the provision of a lower header 22, an upper header 23 and a plurality of heat and water tubes, as particularly shown in Fig. 1.

Referring particularly to Fig. 3, it will be noted that openings 28 are formed through the opposite side walls of each of the lower headers 22 at one end thereof only. These openings are circumscribed by cylindrical hollow bosses 28^b formed on the headers. The bosses at the contiguous sides of the lower headers unite and their length represents the space between the headers. To prevent leakage at the joint between the bosses, a gasket is interposed therebetween.

The opposite ends of the lower headers are connected by short pipes 29 to a mud drum 30 which will serve as a communication between the boiler units and also to collect any sediment that may be in the water.

Due to the arrangement of the bosses 28 and the mud drum 30 all of the boiler units

will be in constant communication and a complete and adequate circulation of water may thus be effected.

The various boiler units are held together by a tie-bolt 31 extending through one end of the lower headers and through the bosses 28 as shown in Figs. 1 and 3. This bolt when tightened insures that all the bosses 28 will be held firmly together without leakage of water through their joints.

At the other ends of the lower headers, spacer blocks 32 are provided to maintain a desired spacing between the lower headers. These spacer blocks are mounted in a manner permitting relative movement of the boiler units to allow for expansion when they become heated.

The tubes of each unit are arranged in sets and the tubes of each set are interconnected intermediate the headers 22 and 23 by short horizontal tubes 33. These short tubes create water columns of unequal weight and unevenness of heat exchanging surfaces and thereby materially increase the circulation of the water in the boiler and also serve as baffles to deflect the upwardly moving heated gases from the compartment 11 so as to obtain a maximum heat exchange in the boiler. It is understood that it is within the scope of the present invention to vary the number of horizontal tubes employed and the number of vertical tubes in each set.

The headers 23 are formed with openings for receiving outlet pipes 34. These pipes are led to the opposite heads of steam drums 35. In the present instance two such drums are shown as mounted upon saddles 36 and enclosed within the upper chamber 13. These drums are connected by means of pipes 37 which in turn are secured to a connection 38. This connection communicates with a super-heater inlet manifold 39 which is connected to a plurality of superheater coils 40. The coils are disposed one in each space between the boiler units and are all connected to a discharge manifold 41. A pipe 42 is connected with this manifold and may be led to a suitable point for delivering the superheated steam to an engine.

It is obvious that the superheater coils will also serve to deflect the upwardly traveling heated gases and retard their progress so as to obtain maximum exchange therefrom.

In the operation of the present invention, the boiler is filled with water substantially to the line indicated at A. This operation may be produced through any suitable connection although not shown in the drawings. Heat is then admitted to the chamber 11 and will pass upwardly through the flue tubes and around the water tubes. It is obvious

that the superheater coils and the horizontal connections between the tubes will act as baffle means to deflect the heated gases and thereby cause a maximum heat exchange in boiler structure. Steam will thus be generated and conveyed through pipes to the steam drums and thence to the superheater coils, from where it may be drawn off as desired. Any sediment and sand in the water will naturally accumulate in the mud drum which may be cleaned as desired.

When a section or unit of the boiler is in need of repairs the tie-bolt may be released and the section disconnected from the steam and mud drums. It may then be removed from the boiler and the necessary repairs made.

The connections between the units are such as to permit slight relative movement between the units to permit them to expand when heated.

To increase the efficiency of the operation of the boiler it is preferred that the combined area of the openings between the lower headers be made three and one quarter times the combined area of the open ends of the flue tubes.

While I have shown the preferred form of the invention, it is to be understood that various changes in its construction may be made without departing from the invention as defined in the appended claims.

Having thus described my invention, what I claim and desire to secure by Letters Patent is:

1. A steam boiler comprising a plurality of boiler units, each unit having horizontally extending upper and lower headers, sets of water tubes extending between the headers, the tubes of each set being connected by water circulating connections intermediate the headers, other tubes extending between the headers intermediate the sets whereby water columns of unequal weight will be formed in each unit, and flue tubes extending upwardly through certain of the water tubes.

2. A steam boiler comprising a plurality of boiler units, each unit having horizontally extending upper and lower headers, sets of water tubes extending between the headers, each set comprising three tubes, horizontal water circulating connections between the tubes of each set intermediate the headers, independent tubes extending between the headers intermediate the sets of tubes, flue tubes extending through two of the tubes of each set and through some of the independent tubes.

ERNEST H. VINCENT.
